Filed Oct. 31, 1974, Ser. No. 519,408

Term of patent 14 years

Int. Cl. D26—02

U.S. Cl. D48—24 A

FIG. 1 is a side elevational view of a flashlight for a telephone receiver showing our new design;

FIG. 2 is a top perspective view thereof;

FIG. 3 is an enlarged perspective view thereof;

FIG. 4 is a front elevational view thereof; and

FIG. 5 is a rear elevational view thereof.

The broken-line showing of a telephone receiver in FIG. 1 is for illustrative purposes only and forms no part of the claimed design.

The side of the flashlight which is not shown is substantially plain and unornamented.

We claim:

The ornamental design for a flashlight for telephone receiver, as shown and described.
